ATTORNEY.

UNITED STATES PATENT OFFICE.

PAUL K. KAPICKAS, OF BROCKTON, MASSACHUSETTS, ASSIGNOR OF ONE-HALF TO
PETER WALATKEVICIUS, OF NANTICOKE, PENNSYLVANIA.

COMBINATION CIGARETTE AND MATCH BOX.

Application filed October 6, 1921. Serial No. 505,721.

To all whom it may concern:

Be it known that I, PAUL K. KAPICKAS, a citizen of Lithuania, residing at Brockton, county of Plymouth and State of Massachusetts, have invented certain new and useful Improvements in Combination Cigarette and Match Boxes, of which the following is a specification.

This invention relates to improvements in combination cigarette case and match holders, and it is the principal object of the invention to provide a case of this character which allows the lighting of a cigarette from a match held in the case and which is ignited after the closure of the case and is protected against the wind.

A further object of the invention is to provide a simple, durable and inexpensive case of this character capable of containing a number of cigarettes, cigarette papers and a match holding member.

The invention consists in a certain novel construction and arrangement of parts fully set forth hereinafter, and specifically pointed out in the appended claims.

In the accompanying drawing forming a material part of this disclosure—

Figure 1 is a front view of a cigarette case constructed according to the present invention, open.

Figure 2 is a horizontal section through the same on line 2—2 of Figure 1.

The case 10 of any desired size, shape and material comprises a frame 11 presenting the customary two parts hingedly connected and provided with the customary snap lock 12 and spring 13 for allowing the case to spring open after disengagement of the catch members of lock 12. The lower smaller part of each part of the case is separated from the larger upper part by a horizontally arranged partition wall 14 extending over both halves of the casing which are hingedly connected in the customary manner as indicated at 15.

In the lower chamber formed by the partition 14 of one half of the case the partition carries an ignition member 16 for a match while the lower chamber formed by the partition 14 of the other half carries a holder 17 for a match 18, the tip 19 of which, when the case is closed strikes the ignition member and is lit protected against the wind by the two halves of the case, while

a cigarette 20 is introduced through the opening 21 in the lower part of the casing.

A package of cigarette paper 22 may be conveniently carried in the upper part of the half casing oppositely disposed to the cigarettes in the other half.

The operation of the device is evidently clear from the above description and needs no further explanation.

It will be clear that changes may be made in the general arrangement, form or shape and in the construction of the minor details without deviating from the scope and spirit of the present invention.

Having thus described my invention what I claim as new and desire to protect by a United States patent is the following—

1. A cigarette case of the class described comprising a spring lock, means for providing four chambers in said case for the carrying of a supply of cigarettes and cigarette papers, a means for holding a match and a means for igniting a match upon the closure of the case.

2. A cigarette case of the character described comprising two hingedly connected halves having a spring catch and a spring for opening the case upon the release of said catch, means for separating each of said halves into two chambers, means in one of said chambers for holding a match, means in the opposite chamber to ignite the match upon the closure of the case, and an opening formed in one of the walls of one of said halves for lighting a cigarette on the match.

3. In a cigarette case of the class described including the customary spring lock, a partition wall separating a larger upper chamber from a lower smaller chamber in each of the halves constituting the case, a holder for a match in one of the lower smaller chambers of the case, and an ignition member in the opposite lower smaller chamber adapted to strike the match carried by said holder upon the closure of the case and to ignite the same, and an opening formed in the side wall of the case for allowing the introduction of a cigarette to be ignited from the burning match.

4. In a cigarette case of the class described comprising two hingedly connected spring controlled parts, a catch for locking both parts in the closed position of the case, a partition wall in the lower part of the

case for forming in each part an upper larger chamber for a supply of cigarettes and an oppositely disposed large chamber for a supply of cigarette papers, two oppositely disposed smaller lower chambers, a match holding member in one of said smaller chambers and an ignition member in the opposite lower smaller chamber so disposed that the tip of the

match held in said holding member will strike the same upon the closure of the case and an opening formed in the side wall of the last named lower chamber for forming a wind shield for the match and allowing the introduction of a cigarette to be lit. 10 15

In testimony whereof I have affixed my signature.

PAUL K. KAPIOKAS.
